UNITED STATES PATENT OFFICE

JOSEPH E. MORRIS, OF MINNEAPOLIS, MINNESOTA.

DESIGN FOR FLOWER-STAND.

Specification forming part of Design No. 6,743, dated July 1, 1873; application filed June 28, 1873.

To all whom it may concern:

Be it known that I, JOSEPH E. MORRIS, of Minneapolis and State of Minnesota, have invented a Design for a Flower-Stand, of which the following is a specification:

The nature of my design is fully represented in the accompanying photographic illustration to which reference is made.

A represents the body of the stand, and B the branches. On the top of the vertical center is a suitable plate for holding a flower-pot, while arranged around the center is a series of similar plates forming a circle resting on

on arms branching out from the body of the stand, as shown in the photograph.

This outer circle of plates may be constructed so as to revolve around the center stand.

What I claim as my invention is—

A design for a flower-stand, in which there is a central plate for holding a flower-pot, with a circle of corresponding plates surrounding the central one, and all ornamented substantially in the manner shown and described.
